Primary Examiner—Lucy Lieberman*(74) Attorney, Agent, or Firm*—Collen IP; Donald J. Ranft(57) **CLAIM**

The ornamental design for a watch dial, as shown and described.

DESCRIPTION

FIG. 1 is a front view of my new, original and ornamental design for the first of embodiment for a watch dial;

FIG. 2 is a rear view thereof;

FIG. 3 is a side view thereof;

FIG. 4 is a front view of my new, original and ornamental design for the second embodiment for a watch dial;

FIG. 5 is a rear view thereof;

FIG. 6 is a side view thereof;

FIG. 7 is a front view of my new, original and ornamental design for the third embodiment for a watch dial;

FIG. 8 is a rear view thereof; and,

FIG. 9 is a side view thereof.

The front of the watch dial in all three of the embodiments is flat and solid.
